UNITED STATES PATENT OFFICE.

GEORGE M. REICHERT, OF MILWAUKEE, WISCONSIN.

CONCRETE-FORM.

1,334,677.

Specification of Letters Patent.

Patented Mar. 23, 1920.

Application filed October 25, 1919. Serial No. 333,189.

To all whom it may concern:

Be it known that I, GEORGE M. REICHERT, a citizen of the United States, residing at Milwaukee, in the county of Milwaukee and 5 State of Wisconsin, have invented certain new and useful Improvements in Concrete-Forms, of which the following is a specification, reference being had therein to the accompanying drawing.

10 This invention relates to certain new and useful improvements in molds for forming straight and circular concrete walls; the object being to provide a form whereby walls of concrete or other plastic material 15 can be readily formed and one which is composed of movable form sections which are adapted to be advanced on the wall; that is, hardened to allow a continuous, harmonious wall of a single piece construction, free from 20 joints and connections to be formed.

Another and further object of the invention is to provide novel means for alining the sections of the mold whereby they will be held in proper alinement so that all 25 danger of displacement is prevented.

Another object of the invention is to provide a mold formed of sections which can be rigidly supported and which are capable of being adjusted in their relation to each 30 other to permit walls of various thicknesses of plastic material to be constructed.

Another and still further object of the invention is to provide novel means for locking the sections of the forms together 35 and for holding the forms in their spaced relation to one another.

Other and further objects and advantages of the invention will be hereinafter set forth and the novel features thereof defined by the 40 appended claims.

In the drawings:

Figure 1 is a top plan view of the mold constructed in accordance with my invention showing the two forms spaced apart 45 in position to receive the plastic material.

Fig. 2 is a side elevation of a series of forms connected together, showing the manner of connecting the same.

Fig. 3 is a detail view of the manner of 50 forming a corner of one of the form sections.

Fig. 4 is a detail top plan view of one of the spacing members showing the same in position.

55 Fig. 5 is a side elevation of the same.

Fig. 6 is a horizontal section showing the construction and manner of locking the form sections together to form an inside corner.

Fig. 7 is an elevation of the same.

Fig. 8 is a detail section showing the 60 manner of forming one of the outside corners and connecting the mold section.

Fig. 9 is an elevation of the same.

Fig. 10 is a top plan view showing the 65 manner of forming an irregular wall.

Fig. 11 is an elevation of one of the locking levers for forming the corner section.

Fig. 12 is an elevation of the same taken from another position.

Fig. 13 is a top plan view of a circular 70 mold constructed in accordance with my invention.

Fig. 14 is an elevation of the same.

Fig. 15 is a detail elevation of one of the spacers.

Fig. 16 is a detail view showing how the 75 spacer feeds down over the mold sections.

Fig. 17 is an elevation showing the locking lever.

Fig. 18 is a section through the same.

Fig. 19 is an elevation of one of the levers employed for locking the superposed mold sections together.

Fig. 20 is a detail view of the spacing member.

Fig. 21 is a section through a portion of the mold showing the joint.

Fig. 22 is an elevation of the same.

Fig. 23 is a top plan view of the inside form of a circular mold showing the scaffolding arrangement.

Fig. 24 is an elevation showing the scaffolding in dotted lines.

Fig. 25 is a detail plan view of one of the locking levers for holding the mold sections together.

Fig. 26 is an elevation of the same.

Fig. 27 is a section showing the manner of connecting the brace rods of the scaffolding to the circular mold sections, and

Fig. 28 is a plan view of the locking lever.

In carrying out my invention, I employ a plurality of duplicate sections 1, which are formed of sheet metal or any other suitable material having vertical angle irons 2, 105 connected to two of the edges and a horizontal angle iron connected to the remaining two edges, the vertical angle irons 2 terminating short of the horizontal angle irons. These corners thus formed are se- 110

cured together by braces 4, as clearly shown in Fig. 3. From the construction thus described, it will be seen that I have provided a mold formed of a plurality of duplicate sections, each section being rectangular in form having an angle iron arranged on one face at the marginal edge thereof. In order to provide means for locking a number of these sections together, I form the horizontal flanges of the angle irons 3, with openings through which is adapted to extend locking levers 5, carried by the upper portion of each form section, and as these levers register the openings of the abutting channel irons, they hold the sections together, as clearly shown in Fig. 2. The vertical channels are also provided with slots through which levers 6 are adapted to pass, so as to lock the abutting channels of the vertical edges and in the construction shown, I have arranged a pair of levers along the upper edge of each form section and along the upper edge of the right hand edge of each form section.

In order to provide means for positioning the mold sections when being assembled so that the levers can be readily forced through the registering openings of the channel irons and for holding said mold sections in their proper position when being assembled, I provide the vertical channels of each section with a notch which is adapted to receive a positioning member 7, one of these positioning members being arranged on each section and fitting in the notch of the adjacent section, and as herein shown, I arrange one positioning member on the top of one section, and the other positioning member on the bottom of the adjacent section, whereby when these positioning members are forced into their notches, the sections will be held.

This construction describes the form used for forming a straight wall and when two of the forms are placed side by side in spaced relation, as shown in Fig. 1, I insert tie rods through openings 8, formed in the channel irons, so that the sections will be bound together. For holding and spacing these sections in proper relation, I provide the horizontal flange of the channels with openings through which the angle end of a spacing member 9, is adapted to extend, said spacing member having a series of openings 10, through which a wedging member 11, is adapted to be driven for securing the mold sections to their proper positions with respect to one another.

Any number of these spacing members can be employed, but I have found that two to a section will be sufficient and in some instances, it is not necessary to employ this number, but of course, I do not wish to limit myself to the number of spacing members as the mold sections when by wires

or rods are used will be held spaced apart securely to receive the plastic material with a very few spacing members.

In constructing the outside corner, I employ a construction as shown in Fig. 8, composed of an angle 12, with the standard locking lever on one side and a flat piece of iron riveted on the other side to clamp the other member which is clearly shown in Figs. 10, 11 and 12. It will be noticed that in this construction, the lever 13 passes alongside of one of the angles and holds the mold sections to the corners. The inside corner as shown in Fig. 6 is formed of angle irons and has a lever 14 for locking the same together, but I do not wish to make any claim to the corner pieces or mode of constructing the same, as I am aware that similar constructions have been used prior to my invention.

In Figs. 13 to 27, I show the various parts of the mold for forming a circular wall and the sections 15, which are formed of sheet metal are provided with vertical angle irons 16, and along the upper and lower edges 90 scraps of band iron 17 in order to allow the sections to be bent on the arc of a circle. The straps of band iron 17, are provided with positioning members 18, as clearly shown and each section 15 of the mold is provided with 95 an angle piece 19, which is slotted. On the inside of each section 15, is an angle iron 20, and one end of which is cut away carries a locking lever 21, which is adapted to extend through the slotted angle pieces 19, 100 so as to lock the superposed mold sections together. The angles 16, are constructed substantially as shown in my mold for forming straight walls and are provided with positioning members 22, and locking 105 levers 23, to enable the sections to be locked together along their vertical edges and the horizontal edges of the mold are locked together, by a lever 21, whereby I am able to assemble a number of these sections to form 110 a circular form of any diameter. The molds are held spaced apart by spacing members 24, which are angle irons having slots at each end as clearly shown in Fig. 20, to receive the upper edges of the mold sections and by this construction the mold sections can be held properly spaced apart and when it is desired to form molds of different diameters different sizes of spacing members 115 are employed.

In forming circular walls it is necessary to employ a scaffolding and in the construction of Figs. 23 to 27 I show a scaffolding construction adapted to be used in connection with the circular mold constructed in accordance with my invention and comprising a series of ring sections 25, which are formed of angle irons and are locked together at their ends by levers 26, said ring sections fitting in notches formed in a member 26', 130

secured to the central angles 20, and when the ring composed of the sections 25 placed is in position with the inside circular mold, the mold will be reinforced. In order to 5 provide means for strengthening the ring formed by the sections 25, I provide a series of braces 27, which are connected to the ring sections by pins 28, and these braces 27 are connected together by braces 29, the ends of 10 the angles being cut away so that they rest upon the rings and abutting braces whereby I am able to form a ring of any diameter desired as by increasing the ring sections and number of braces, the scaffolding con- 15 struction can be increased any size so as to support a circular form constructed in accordance with my invention of any size desired.

The locking levers employed as shown in 20 Fig. 28, connecting the vertical edges of the mold sections together, are constructed identical with the straight and circular form sections and are provided with notches 30, which are adapted to engage the edge of the 25 notches in the abutting angle irons secured to the edges of the mold sections, so as to securely lock the sections together. I am aware that levers or locking devices have been employed for connecting the mold sec- 30 tions together prior to my invention, but the construction of these locking devices is such that they have not been satisfactory in use and I have devised a construction of mold and manner of locking the same where- 35 by a plurality of sections can be assembled in such a manner that strong and durable form either straight or circular in form can be produced.

While in the specification I have not speci- 40 fied how the straps of band iron and angle irons are secured to the sheet metal form sections, it is of course understood that they can be riveted or welded thereto, and I do not wish to limit myself to any particular 45 manner of forming these mold sections in respect to the manner of connecting the same to the sheet metal bodies, but what I do claim is the manner of positioning and rigidly securing the sections together.

50 What I claim is:

1. A concrete mold formed of a plurality of duplicate form sections having angle irons secured to their vertical edges pro- 55 vided with registering openings, levers pro- vided with notches adapted to extend

through said openings for locking said sec- tions together, members carried by the vertical angle irons of adjacent sections extending respectively into notches formed in said angle irons of each other for positioning 60 said members, and horizontal angle irons be- ing provided with slots and spacing mem- bers arranged on said angle irons, said spac- ing members having angled ends extending 65 into notches of one form section, and pro- vided with a series of slots through which wedges are adapted to extend for holding said sections in spaced relation to one an- other.

2. A concrete mold formed of inner and outer members each formed of a plurality of sections interlocked together, and spaced apart to form a mold, the inner section of 70 said mold being provided with notched mem- bers and a scaffolding construction composed 75 of a plurality of segments interlocked to- gether to form a ring seated in the notches of said members, said ring sections being connected together by a plurality of braces.

3. A concrete mold formed of a plurality 80 of form sections interlocked together by levers, said sections being provided with notched members, a scaffolding construction formed of a plurality of segments locked to- 85 gether by levers to form a ring arranged in the notches of said members, said ring being provided with braces connected together by braces to provide an interchangeable scaf- 90 folding construction for increasing and de- creasing the size of said ring.

4. A circular mold for concrete structures composed of inner and outer members each formed of a plurality of form sections hav- 95 ing angle irons along their vertical edges and strap irons along their horizontal edges the strap irons being provided with slotted 100 angles, members carried by the upper strap iron of each section for positioning said sec- tion in respect to the abutting section, each of said sections carrying levers adapted to extend through the registering slots of the vertical angle irons for locking said sec- tions together, and spacing members for spacing said members apart.

In testimony whereof I hereunto affix my 105 signature in the presence of two witnesses.

GEORGE M. REICHERT.
